ATTORNEY

UNITED STATES PATENT OFFICE.

HOWARD A. POST, OF WINFIELD, KANSAS.

TELEPHONE-MOUTHPIECE ATTACHMENT.

1,297,490.

Specification of Letters Patent. Patented Mar. 18, 1919.

Application filed February 28, 1918. Serial No. 219,649.

To all whom it may concern:

Be it known that I, HOWARD A. Post, a citizen of the United States, residing at Winfield, in the county of Cowley and State 5 of Kansas, have invented certain new and useful Improvements in Telephone-Mouthpiece Attachments, of which the following is a specification.

This invention relates to telephones, and 10 more especially to antiseptic protectors for the mouth pieces thereof; and the object of the same is to produce a protector which involves the use of sanitary paper interposed between the lips of the operator and mouth 15 piece, with means for removing the paper each time the telephone is used.

This and other objects are accomplished by constructing the attachment in a manner hereinafter more fully described and 20 claimed, and as shown in the drawings, wherein:—

Figure 1 is a front elevation of a mouth piece with this attachment applied,

Fig. 2 is a sectional view on the line 2—2 25 of Fig. 1,

Fig. 3 is a plan view with the drum partly broken away.

In the drawings the letter M designates the mouth piece of an ordinary telephone whose details need not be elaborated here. Secured thereto in any appropriate manner is a plate 1, the form of attachment shown in Fig. 3 being by means of tangs 2, this plate being provided with a large central 35 hole 3 coincident with the bell of the mouth piece end and of nearly the same size. The plate carries in the present instance at its left end a drum 4 which has a hinged door 5, and at its right end a spring clip 6 having 40 a thumb piece 7. Now a roll of paper as indicated at 8 is inserted in the drum, and its free end led across the face of the plate, over the hole 3, and under the clip 6 as best seen in Figs. 1 and 3.

45 When an operator desires to use the phone,

he grasps the edge of the paper at 9, draws it out until a fresh stretch extends across the hole 3, and tears it off, and then he talks through the paper into the bell mouth end of the phone as usual. The paper should be 50 quite thin and sterilized in any approved manner, and obviously no part of his lip of his mustache can come in contact with the mouth piece of the phone and therefore complete sanitation is effected. I might add 55 that it is very frequently the case that a person using the phone has need for a little piece of paper, as when some memorandum is to be written down; and this attachment provides the paper ready at hand when such 60 occasion arises. From time to time the door 5 of the drum can be opened and a new roll of sterilized paper inserted in a manner which will be clear. While I have shown the drum at the left and the clip at the 65 right, this might be reversed, or the drum could be at the top and the clip at the bottom if desired. All parts will preferably be of metal, suitably ornamented so as to prove attractive, and the attachment should be in- 70 expensive and popular.

What is claimed as new is:—

The herein described attachment for telephone mouth pieces, the same comprising an upright plate having a hole coincident with 75 that of the mouth piece, tangs on said plate for securing it to the mouth piece, a drum at one edge of the plate for containing a roll of sterilized paper, and a long upright clip at the other edge of the plate and 80 under which the paper passes, the clip having a thumb piece, the whole for use substantially as described.

In testimony whereof I affix my signature in presence of two witnesses.

HOWARD A. POST.
